FUEL BURNING DEVICE

Original Filed Oct. 1, 1923

Patented Mar. 26, 1929.

1,706,395

UNITED STATES PATENT OFFICE.

LOYD I. ALDRICH, OF PEORIA, ILLINOIS, ASSIGNOR TO PREFERRED OIL BURNERS, INC.,
OF PEORIA, ILLINOIS, A CORPORATION OF ILLINOIS.

FUEL-BURNING DEVICE.

Application filed October 1, 1923, Serial No. 665,785. Renewed February 16, 1926.

My invention relates to fuel burning devices and more particularly to a drain or oil sump therefor.

The object of my invention is in the provision of a drain pan or fuel sump for a fuel burning device whereby the excess fuel that drips or leaks from portions thereof will be caught in said sump and returned to the device for consumption upon a succeeding movement thereof.

Another object of my invention is in a specific means for returning excess fuel from a sump disposed beneath the main portions of a fuel burner to said burner.

15 A further object of my invention is in the provision of a fuel sump for catching the waste or excess fuel from a fuel burning device and means for automatically returning said waste fuel to the burner during the 20 operation thereof.

Other objects of my invention will appear in the following specification taken in connection with the annexed drawing in which:—

Figure 1 is a plan view of the fuel sump 25 with the burner apparatus removed.

Figure 2 is a side elevation partially in section of a fuel burner outfit showing the relation of the fuel sump and drain mechanism thereto.

30 I have shown in the drawings my fuel sump and drain means, in connection with my fuel burning device which has been described in detail in my co-pending application Serial No. 633,272 filed April 19th, 1923. However, 35 my present sump and drain means is adapted to be used in connection with any fuel burning outfit wherein a pump means is provided for placing air under pressure for purposes of atomization. In the fuel burning device

40 described in detail in my co-pending application and which is here illustrated, I have provided an air pump for placing air under pressure. This pump is shown at 10 in the present application and briefly, includes means for drawing air thereinto and placing said air under pressure. I do not wish to be limited to any specific type of pump and as a matter of fact any means for drawing air into a fuel burning outfit would accomplish the same 45

50 result in connection with the following:—

Fuel burning outfits for house installation have developed to a very high degree. However, due to the numerous moving portions therein and to the high speed at which they 55 operate there is always a considerable amount

of leakage therefrom, which, unless otherwise disposed of, drains to the floor, usually the basement, upon which the burning device is located. Not only is this waste fuel difficult to clean up, but also and much more important is the fact that it is dangerous because of the combustible qualities contained therein. The majority of fuels used in the present fuel burning devices are easily ignitable and for this reason every precaution must be 60 taken to prevent any leakage from the device. The fact that the device from which the excess fuel leaks or drains is adjacent a furnace wherein there is a tremendous heat is 65 an added reason for preventing it.

70 Normally a plate is disposed beneath the fuel burning device and is perhaps capable of retaining therein a certain quantity of the waste fuel. However, such means only temporarily retains the waste fuel and even then 75 there is no means for immediately disposing of this dangerous accumulation.

75 As said before, my drain and sump member is adapted, to be used in connection with fuel burning devices wherein air is taken in for 80 the purpose of atomization, and in the present structure I have illustrated at 10 an air pump adapted normally to withdraw air thereinto and place it under pressure. Disposed below my fuel burning outfit designated generally as X, I have placed a fuel sump 85 generally described as 11, every portion of which slopes toward the main sump 12 wherein a drain means to be described, is disposed. In other words, my fuel sump 11 underlies 90 every portion of the burning device from which there is liable to be a leakage of fuel, and in case of such leakage the fuel runs by gravity to the main sump 12 disposed at the 95 lowest point.

I have not illustrated all of the supporting means of the burning device and sump, but leg portions similar to the one shown at 13 are adapted to support the sump and from which the burning device is similarly adapted to 100 be rigidly supported. Means for draining the sump after an accumulation of oil has leaked thereinto is provided in the following mechanism:—

An air inlet pipe 14 leads from the air 105 pump 10 to a muffler 15, said pipe intermediate its length, having the return bend 16, passing thru the main sump 12. The muffler 15 encloses the open end of the air pipe 14, the air inlet into said pipe being thru the re- 110

stricted opening or intake 17 whereby movement of the air pump and the consequent drawing in of the air thru the restricted opening produces a partial vacuum within the muffler 15. The bend 16 in the air pipe passes thru the main sump portion and is supported therein by means of the bracket 18, which actually forms the bend in the air pipe, said bracket engaging the sump as shown at 10 18^a and 18^b. A vent 19 in the lower side of the bend 16 permits the waste fuel to seep into the bend. However, there is a screen 20 disposed below the vent 19 in connection with the lower end of the supporting bracket for the purpose of straining the fuel before its 15 return to the burner for consumption.

The operation of my drain for the fuel sump is as follows:

Either activity or inactivity of the burner, 20 as said before, results in a varying amount of fuel leaking from various portions of the outfit. This waste fuel drains, due to the particular formation of the sump, to the lower-most point thereof, filling the main sump 25 wherein is disposed the bend in the air pipe connecting the liquid air pump and the vacuum muffler. The waste fuel that has drained into the main sump passes thru the strainer and thence thru a vent 19 into the return 30 bend, subsequently closing said pipe with an oil seal between the liquid air pump and the muffler. Normal activity of the burner results in the withdrawal of air thru the restricted opening 17, thru the air pipe 14 and 35 into the air pressure pump. This withdrawal of air thru the restricted intake results in a partial vacuum within the closed muffler with

the result that whenever the waste fuel rises to such a point as shown in Figure 2 of the drawing; that is, filling the return bend in 40 the air pipe, then the waste fuel will adhere to the air and be carried up to the liquid air pressure pump.

You can see from the above that whenever waste fuel drains into the sump to such an extent as to close the return bend, either during the operation of the device or during its inactivity, the subsequent movement of the air pump will return said fuel again to the burner.

The automatic draining of the fuel sump disposed below the burner device results in not only a clean apparatus, but also prevents any possibility of fire due to the leakage of fuel of high combustible quality.

What I claim is:

1. The combination with a fuel burning device including an air pressure pump, of a waste fuel drain including a sump, a partial vacuum muffler and an air inlet pipe connecting the air pump and muffler and having a bend therein within the sump portion, said pipe also having a vent adjacent the sump.

2. The combination with a fuel burning device, including an air pressure pump, of a waste fuel sump, means for automatically draining the fuel sump including an air pipe having a return bend within the fuel sump and having an opening thereinto, a closed container disposed about the open end of the air pipe, said air pipe having an air inlet part adjacent said container.

In testimony whereof I affix my signature.
LOYD I. ALDRICH.
